GLAZING CLIP

Alvin C. Goddard, Forest Hills, and Raymond P.
Le Viness, Queens Village, N. Y.

Application March 12, 1932. Serial No. 598,340

10 Claims. (Cl. 189—78)

This invention relates to means for securing panels in frames.

More specifically it relates to panelled construction such as the interior partitioning of buildings 5 and to the holding of the panels in their frames by means which are adjustable to compensate for varying thicknesses of panel.

Our invention comprises short brackets or clips commonly called "glazing clips" which are positioned at intervals about the panel frames and which have cooperating stud and slot engagement with the frames whereby they may be adjustably moved to and from the panels.

One of the objects of our invention is to provide a device of the character described which will be adjustable through a wide range to accommodate varying thicknesses of panel and to prevent breakage in the use of glass panels by compensating for inequalities in the thickness 20 thereof.

Another object is to assemble and hold the panel in position without the aid of putty or the like.

Another object is to provide a device simple in 25 its construction and operation and inexpensive in its production.

These and other objects will more fully hereinafter appear.

While our invention is susceptible of use with 30 framework of wood or the like, we shall for purposes of illustration describe it as applied to metallic framing.

In the drawing:

Fig. 1 is a perspective view showing a panel 35 frame with the panel held in position therein according to our invention;

Fig. 2 is a side elevational view of the same;

Fig. 3 is a cross-sectional view taken on the line $x-x$ of Fig. 2, and

40 Fig. 4 is a cross-sectional view such as on the line $y-y$ of Fig. 2 but illustrating a slight modification.

Referring to the drawing, the panel framing, here shown as being made from sheet metal, indicated at 1, has formed integrally therewith a molding member 2 which extends about the inner side of the panel frame and functions as an abutment against which one side edge of the panel 3 seats.

45 The frame 1 is provided with a series of elongated slots shown as what may be termed double keyhole slots in that they have an enlargement indicated at 4 and two diverging extensions as 5 and 6, for a purpose which will hereinafter appear.

As a means for engaging the other side edge of the panel and holding it firmly against the abutment 2 we employ a plurality of angular sheet metal members 7. These members, which we shall hereinafter refer to as glazing clips or 60 clips, are provided with panel engaging arms 8 and frame engaging arms 9.

The clips 7 are provided with headed stud members 10 which are adapted to engage and cooperate with the slots in the frames. This stud 65 member 10 is herein shown as formed integral with the clip 7 and may be so made by drawing out from the central portion of the arm 9 a deep cylindrical protuberance. The top of the protuberance is then cut away and the edges of the 70 metal are bent back upon themselves to form the head. This headed stud, however, may be provided in any other suitable manner.

In operation, after the panel 3 has been seated against the abutment 2, the headed studs 10 of the 75 clips 7 are passed through the enlarged portion 4 of the slots in the frame and the clips are then moved through the elongated slot extensions 5 and 6 until the arms 8 are brought into intimate contact with the panel.

80 The slots are provided with two-way extensions primarily so that it will not be necessary, in fabricating the frame members 1, to make right and left elements, as would be necessary with a one-way slot if it were desired to have them run in 85 a downward direction toward the panel. By utilizing two-way slots, the frame members 1 are interchangeable for both sides of the frame. In addition to this advantage it is possible to employ 90 two glazing clips in each slot, one of which will seat in the upper extremity of the extension 5 and the other in the lower extremity of the extension 6.

In any event it is to be noted that the elongated extensions of the slots are slightly narrower 95 than the heads of the studs 10 and that they approach the panel at a slight angle so that the clips will be retained in locking position frictionally by engagement with the panel and slot.

The clips 7 are provided with lateral flanges 11 100 and 12, the flange 11 being slightly offset from the arm 8 and the flange 12 being slightly rounded or bent inward. These flanges serve to resiliently support a finish or molding member 13 short broken away sections of which are shown 105 in place in Fig. 1. These finish molding members, which are usually complements of the abutment 2, run through the length and width of the frame and engage the flanges of all of the clips.

110 These finish members are provided with op-

posed flanges 14 and 15 and they are positioned by hooking the flange 14 over the offset flange 11 after which the flange 15 is pushed into position over the rounded edge of the flange 12.

8 It will be noted that when this finish member is positioned in engagement with the clips it will resist any tendency which they may have to back away from the panel because of vibration or shocks.

10 When our device is used with glass panels it may be found desirable to provide cushioning means between the panel and one of its side engaging members. This may be accomplished by placing a piece of felt, rubber or any suitable cushioning material between the panel and the flange 8. We have shown for this purpose, in full lines in Fig. 3 and in section in Fig. 4, a band or strip of rubber 16 which surrounds the flange 8.

20 While one of the purposes of our invention is to eliminate the use of putty and its attendant objectionable features, nevertheless a surrounding filler of putty, rubber, felt or the like may be employed to accomplish a tight seal, as shown at 17 in Fig. 4.

25 Our invention is adaptable for use with panels of any suitable material such as glass, wood, composition or the like and will accommodate panels of unequal thickness and panels of a wide range of thicknesses, and will obviate breakage of fragile panels.

30 The invention is susceptible of many changes in form and application without departure from its spirit and scope. Instead of utilizing the abutment 2, for instance, we may employ spaced projections on one side of the frame, or we may employ glazing clips on both sides of the panels.

We claim:

40 1. The combination with a panel frame and panel of means for holding the panel in the frame comprising a clip provided with a stud and an elongated stud-receiving slot in the frame, said slot extending at an angle acute to said panel, said stud and slotted frame portion cooperating upon relative movement between said clip and frame to hold said panel in the frame.

45 2. The combination with a panel frame and panel of means for holding the panel in the frame comprising an angle clip one leg of which engages the panel and the other leg of which is provided with a stud, and an elongated stud-receiving slot in the frame extending at an angle acute to the panel, said stud and slotted frame portion cooperating upon relative movement between said clip and frame to hold said panel in the frame.

50 3. The combination with a panel frame and panel of means for holding the panel in the frame comprising an angle clip one leg of which engages the panel and the other leg of which is provided with a stud, an elongated stud-receiving slot in the frame extending at an angle acute to the panel, and cushioning material on the panel engaging leg positioned between the latter and the panel, said stud and slotted frame portion cooperating upon relative movement between said clip and frame to hold said panel in the frame.

55 4. The combination with a frame and a panel, the frame having means engaging one side edge of the panel, of means engaging the opposite side edge of the panel, said means comprising a stud, and a stud-receiving slot in the frame arranged at an angle acute to the panel, said stud and slotted

frame portion cooperating upon relative movement between said clip and frame to hold said panel in the frame.

60 5. The combination with a panel frame having an abutment and a panel engaging the abutment, of adjustable means for holding the panel against the abutment comprising a clip having a stud, and an elongated stud-receiving slot in the frame arranged at an angle acute to the panel, said stud and slotted frame portion cooperating upon relative movement between said clip and frame to hold said panel in the frame.

65 6. The combination with a panel frame having an abutment and a panel engaging the abutment, of adjustable means for holding the panel against the abutment comprising a clip having a headed stud, and an elongated keyhole stud-receiving slot in the frame arranged at an angle acute to the panel, said stud and slotted frame portion cooperating upon relative movement between said clip and frame to hold said panel in the frame.

70 7. The combination with a panel frame having an abutment and a panel engaging the abutment, of adjustable means for holding the panel against the abutment comprising a clip having a stud, a stud-receiving slot in the frame arranged at an angle acute to the panel, and a finish member resiliently engaging said clip, said stud and slotted frame portion cooperating upon relative movement between said clip and frame to hold said panel in the frame.

75 8. The combination with a panel frame having an abutment and a panel engaging the abutment, of adjustable means for holding the panel against the abutment comprising a clip having a stud, a stud-receiving slot in the frame arranged at an angle acute to the panel, and a member holding said clip in locking position and having resilient engagement therewith, said stud and slotted frame portion cooperating upon relative movement between said clip and frame to hold said panel in the frame.

80 9. The combination with a panel and a frame therefor provided with an abutment, against which the panel seats, of adjustable means for locking the panel against the abutment comprising a clip having a stud and lateral flanges, of an elongated stud-receiving slot in the frame arranged at an angle acute to the panel whereby the clip may be moved to and from the panel, and a finish member resiliently engaging the lateral flanges, said stud and slotted frame portion cooperating upon relative movement between said clip and frame to hold said panel in the frame.

85 10. The combination with a panel and a frame therefor having a ledge engaging one side edge of the panel, of adjustable means engaging the other side edge of the panel, said means comprising a plurality of clips having headed studs and lateral flanges, of a plurality of triangular stud-receiving slots in the frame both arms of which extend at angles acute to the panel, said slots having enlarged openings at their apices for the reception of the headed studs, and a member holding said clips in adjusted position having resilient engagement with the lateral flanges of the clips, said stud and slotted frame portion cooperating upon relative movement between said clip and frame to hold said panel in the frame.
